UNITED STATES PATENT OFFICE

111,570

DESIGN FOR A BIRD CAGE

Norman A. Olson, Oak Park, Ill.

Application November 18, 1937, Serial No. 72,994

Term of patent 3½ years

To all whom it may concern:

Be it known that I, Norman A. Olson, a citizen of the United States and a resident of Oak Park, in the county of Cook and State of Illinois, have invented a new, original, and ornamental Design for a Bird Cage, of which the following is a specification, reference being had to the accompanying drawing, forming a part thereof.

The figure is a perspective view of a bird cage showing my new design.

I claim:

The ornamental design for a bird cage as shown.

NORMAN A. OLSON.
